United States Patent Office

Des. 191,804
Patented Nov. 21, 1961

191,804

BOTTLE

Jack Bloch, Fort Worth, Tex., assignor to Loma Industries, Fort Worth, Tex., a corporation of Texas

Filed Sept. 21, 1960, Ser. No. 62,228

Term of patent 14 years

(Cl. D58—6)

FIG. 2.

FIG. 4.

FIG. 1.

FIG. 3.

The rear and side not shown are substantially the same as the front and side shown, respectively.

I claim:

The ornamental design for a bottle, as shown and described.
